(57) **CLAIM**

The ornamental design for a ceiling lighting equipment for elevator, as shown and described.

DESCRIPTION

FIG. 1 is a front, top, and right side perspective view of a ceiling lighting equipment for elevator, showing a first embodiment of our new design;

FIG. 2 is a front view thereof;

FIG. 3 is a rear view thereof;

FIG. 4 is a top view thereof;

FIG. 5 is a left side view thereof;

FIG. 6 is an enlarged cross-sectional view taken along line **6-6** in FIG. 2, with the internal system omitted thereof;

FIG. 7 is a front, top, and right side perspective view of a ceiling lighting equipment for elevator, showing a second embodiment of our new design;

FIG. 8 is a front view thereof;

FIG. 9 is a rear view thereof;

FIG. 10 is a top view thereof;

FIG. 11 is a left side view thereof; and,

FIG. 12 is an enlarged cross-sectional view taken along line **12-12** in FIG. 8, with the internal system omitted thereof. The broken lines in the drawings illustrate portions of the ceiling lighting equipment for elevator which form no part of the claimed design.
